CLAIM

We claim the ornamental design for a dual-grip gadget handle, as shown and described.

DESCRIPTION

FIG. 1 is a top frontal perspective view of a dual-grip gadget handle according to our new design;

FIG. 2 is a front view of the dual-grip gadget handle shown in FIG. 1;

FIG. 3 is a back view of the dual-grip gadget handle shown in FIG. 1;

FIG. 4 is a left side view of the dual-grip gadget handle shown in FIG. 1;

FIG. 5 is a right side view of the dual-grip gadget handle shown in FIG. 1;

FIG. 6 is a top view of the dual-grip gadget handle shown in FIG. 1; and,

FIG. 7 is a bottom view of the dual-grip gadget handle shown in FIG. 1.

The ornamental design which is claimed is shown in solid lines in the drawings. The broken lines in the drawings are for illustrative purposes only and form no part of the claimed design.
